CLAIM

The ornamental design for a solar laser LED spot light, as shown and described.

DESCRIPTION

FIG. 1 is a perspective view of a solar laser LED spot light, showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The even-broken line in the figure drawing views represents unclaimed environment structure of the solar laser LED spot light only and forms no part of the claimed design.
